KEY RING

William H. Meeker, Rochester, N. Y., assignor
to Hickok Manufacturing Co. Inc., Rochester,
N. Y., a corporation of New York

Application June 8, 1950, Serial No. 166,947

4. Claims. (Cl. 70—459)

1

This invention relates to an improved key ring. The invention is more particularly directed to a key ring of substantially circular design and embodying two main component elements, one of which is in the form of a cut out or mutilated key carrying disc, and the other is in the form of a hood, and the said disc and hood being associated together in such a manner that one of the said elements is movable relative to the other in order to expose a gap for placing a key on the key ring or removal of the same therefrom, or for closing the gap and thus maintaining the keys on the key ring.

The invention is more particularly directed to a key ring of the aforesaid hooded type and wherein there is embodied a latch structure which serves to positively maintain the key holding portion of the key ring in a closed position and, when the said key retaining or holding portions thereof is in open position to receive a key or keys or for the removal of a key or keys therefrom, the said latch, upon a simple movement of one of the elements relative to the other, will result in the key ring being closed and serve to effectively maintain the keys thereon.

Still more specifically, the present key rings are of the type that are constructed of the two main component elements, namely the mutilated or cut out disc like key holder and retainer, a hood element that covers a portion thereof, and these two elements being pivotally connected together and embodying between the same, a latch structure which, when operated, serves to allow one of the elements to be rotated relative to the other to either open or close the key ring.

There are many prior key ring structures and, in the main, they consist of either the simple split ring type, and in some instances, the more elaborate type involving pivoted and other catches or latches associated therewith and, of course, the type of key holders that are embodied in suitable cases, such as metal or leather cases. While the prior art key rings perform their intended functions quite satisfactorily, the key ring of the present invention, due to its simplicity of structure and the novel combination of the component elements, is such that it is capable of easy and simple manipulation for placing on or removing from and the retaining of keys that are carried thereon without fear of loss or unintentional disconnection or opening of a gap by means of which one or more keys could be accidentally removed or lost from the key ring.

In the prior art devices, some of the latch

2

structures and other pivoted retaining means are such that they may be accidentally moved or opened and a key or keys lost therefrom where this does not happen with regard to the present key ring.

In view of the foregoing, it is, therefore, an object of the invention to provide a relatively simple key ring structure fabricated from metal or the like and including a minimum number of component and cooperative elements that are compactly associated with each other and serving to effectively maintain a key or keys thereon.

Another object of the invention is to provide a key ring consisting of two major component elements, one of which is in the form of a substantially circular disc-like cut out or mutilated key holder or carrier, and the other of the elements being in the form of a substantially arcuate shaped hood that is pivotally or rotatably associated with the disc-like key holder or retainer, and the disc-like element having a gap therein at one side edge which is opened and closed by movement of one of the elements relative to the other.

Another object of the invention is to provide a key ring consisting of two major component elements, one of which is in the form of a substantially circular disc-like cut out or mutilated key holder or carrier, and the other of the elements being in the form of a substantially arcuate shaped hood that is pivotally or rotatably associated with the disc-like key holder or retainer, and the disc-like element having a gap therein at one side edge which is opened and closed by movement of one of the elements relative to the other, and further, wherein there is a novel latch structure that is in interengagement between the hood and the disc-like key carrier or holder.

Another object of the invention is to provide a hooded type key ring wherein the hood surrounds a portion of a disc-like key retainer or holder, and where the hood is moved relative to the disc-like key retaining holder or vice versa so as to expose or cover a gap for reception of keys therein and which gap is in the disc-like key holder or retainer and is either opened or closed by the said hood as the case may be.

Another object of the invention is to provide a hooded type key ring wherein the hood surrounds a portion of a disc-like key retainer or holder, and where the hood is moved relative to the disc-like key retaining holder or vice versa so as to expose or cover a gap for reception of keys therein and which gap is in the disc-like

key holder or retainer and is either opened or closed by the said hood as the case may be, and further wherein there is an interengaging lock or latch structure between the hood and the disc-like key carrier or holder, and which latch serves to either maintain the gap in the disc-like key retainer or holder open or closed, and when closed, preventing accidental displacement of one or more keys from the key ring.

Another object of the invention is to provide a key ring of the aforesaid type wherein there are a minimum number of parts all of which are prefabricated and which can be made from a stamping operation and capable of being readily and easily assembled into the final key ring formation.

With the above and other objects in view, the invention consists in the construction and novel combination and arrangement of parts herein-after fully described, illustrated in the accompanying drawings and pointed out in the claims hereto appended, it being understood that various changes in the form, proportions, and minor details of construction, within the scope of the claims, may be resorted to without departing from the spirit or sacrificing any of the advantages of the invention.

In the drawings:

Fig. 1 is a front elevational view of the key ring with a key chain attached thereto at one end and the other end of the key chain having thereon a suitable fastener and showing the key ring in its locked or closed condition;

Fig. 2 is a view similar to Fig. 1 but showing certain parts in section and others in elevation and showing the key ring in an open condition and exposing the gap into which a key or keys may be inserted;

Fig. 3 is an exploded perspective view of all of the component elements that comprise the key ring structure;

Fig. 4 is a transverse sectional view taken substantially along the lines 4—4 of Fig. 1 looking in the direction of the arrows;

Fig. 5 is a view similar to Fig. 4 taken substantially on the lines 5—5 of Fig. 1;

Fig. 6 is a transverse sectional view taken substantially along the lines 6—6 of Fig. 1; and

Fig. 7 is a vertical sectional view taken substantially along the line 7—7 of Fig. 1.

The invention will be more readily understood by referring to the drawings in detail wherein the same numerals or characters denote the same parts or component elements in the several figures thereof.

The key ring is denoted generally at 8 and it will be seen that, as depicted, the exterior contour and general outline thereof is substantially circular and disc-like but, of course, it is to be understood that the invention is not to be limited to the precise outline and contour or shape. The key ring consists of two major elements namely the disc-like cut out or mutilated key carrier or holder 9 and the two substantially arcuate or sector shape hood sections 10 and 11. The minor or remaining elements of the key ring include the latch 12 and the spring 13 which normally urges the latch outwardly as hereinafter more fully described, the prefabricated solid rivet 14 having an enlarged central portion 14a and reduced end portions 14', and the hollow rivet 15.

The substantially disc-shaped and preferably flat key carrier or retainer 9 has a substantially semi-circular cut out formation or design 16 therein and which is at the bottom portion there-

of. This substantially circular cut out formation has a closed end 17 and an open end or key receiving and removing gap 18. Substantially centrally of the disc-like key carrier and holder there is a hub or bearing portion 19 which has an opening 20 therein, which opening is of a diameter to receive the enlarged portion 14a of the rivet therein. This bearing portion has an outer edge 21 and its oppositely disposed surfaces 22 are substantially smooth and flat. There is a cut out slot 23 in this disc, the inner end of which 24 is in substantially vertical alignment with the opening 20, and this slot 23 open at the periphery of this disc as denoted at 25 and slightly inwardly thereof and on both sides, the slot is undercut as at 26, and which undercut formation receives therein a part of the latch 12 more fully described hereinafter. By forming the semi-circular opening 16 in the disc and, further, by forming the gap 18, this, of course, results in providing a substantially semi-circular key carrying or holding arm 27 which has a free end portion 28 and the outer peripheral portion of the same is cut away or notched to provide a shoulder 29 for a purpose later described.

The latch 12 and the spring 13 are so proportioned and dimensioned that the spring is positioned in the reduced portion 23 of the slot and one end thereof 30 rests on the closed end 24 of the slot 23, and the other end 31 of the spring 13 is positioned in a slot or recess 32 in the bottom of the latch member 12. This latch member 12 has similarly formed side extensions 33, the shape of which are in conformity with the undercut portions 26 formed in the slot 23 and the latch has a reduced head formation 34. Thus, when the spring 13 is mounted in the slot 23 and the latch 12 is positioned in the outer portion of the slot where the undercut formation occurs, the spring and latch are maintained in their proper association with the slot in the disc-like key ring retainer and holder. It is to be understood, of course, that the extensions 33 at the opposite sides of the latch 12 are so dimensioned with respect to the undercut portion 26 of the slot, that the latch 12 will be permitted to move inwardly and outwardly in this undercut portion of the slot. In other words, the undercut portion 26 of the slot 23 is such that it is of greater depth than the thickness or depth of the extensions 33 of the latch 12. It will thus be clear that the key carrying and supporting element consists of a disc having an arcuate slot spaced from the periphery of the disc to form the key carrying or holding arm 27, and closed at one end and open at the other end by means of the gap which provides an entrance to the arcuate slot 16. The disc is provided at a point spaced from the closed end of the arcuate slot 16 with a radial slot 23 extending inwardly from the periphery of the disc and receiving the latching member for holding the hood in its open and closed positions.

The hood element of the key ring, as aforesaid, consists of the two arcuate or sector shaped sections 10 and 11, which are substantially similarly formed but there necessarily being right and left sections, the numeral 10 indicating the left section and the numeral 11 indicating the right section. Each of these hood sections includes a substantially arcuate or sector shaped wall 35 and a portion of the outer edge of each section includes a curved flange 36 and an integral outstanding ear 37, and each of which ears has an opening 38 therein. Additionally, the outer edge portions 39 and 40 of each of the hood sections

10 and 11 are free of any flange formations whatsoever, and intermediate of the same and bent inwardly, there is a continuance 41 of the aforesaid flanges 36. Further, each of the sector or arcuate shaped hood sections 10 and 11 include at their apexes similarly formed caps denoted generally at 42, and these caps each include a substantially circular flange 43, and substantially centrally thereof, the caps have an opening 44 therein. These caps 42 are of concavo convex formation and, of course, they are integral with the sector or arcuate shaped hood sections 10 and 11 and at the apex, so to speak, of these two sections.

The sector or arcuate shaped sections 10 and 11 are simply brought together on opposite upper sides of the disc-like key carrier or holder with the rivet 14 positioned therein and, when they are thus brought together, the edges 45 and 46 of the flanges 36 and 41, respectively, abut and, likewise, the inner surfaces of the outstanding tongues 37 also abut and this results in the cap formations 42 surrounding the hub formation 19 and aligning the openings 44 in these cap formations with the opening 20 in the disc-like key carrier and holder 9 and also aligning the openings 38 in the ears 37 and, of course, when these two sector or arcuate shaped hood sections are thus brought together, with the reduced ends 14' of the rivet 14 projecting outwardly through the opening 44, the upper portion of the key ring is enclosed and, of course, likewise, the spring and the latch are also enclosed except for the head portion of the latch. In order to assemble the hood sections in their proper relationship with the disc-like section or member of the key ring, preferably the enlarged central portion 14a of the solid rivet 14 is first inserted into the opening 20 with the reduced ends 14' projecting beyond opposite sides thereof and with these reduced ends extending through and beyond each of the openings 44 in the opposite sections constituting the hood, and the extreme ends of the rivet are then upset to hold the sectional hood in place, and, additionally, these two sections of the hood are held together by the hollow rivet 15 which may initially be flanged over as at 15a, if desired, that is inserted in the aligned openings 38 in the ears 37 and the free ends projecting beyond the same swaged over as at 15a. Thus, it will be seen that the hood section or element of the key ring and the disc-like key carrier or holder are fixedly and properly associated with each other. The rivet 14 forms a bearing for rotation of the disc 9 relative to the hood sections 10 and 11 when they are brought together or vice versa.

When the enlarged portion 14a is positioned in opening 20, the opposite ends of the said enlarged portion extend slightly beyond the opposite side faces of the hub or central portion 19 of the key carrier disc 9, see Figs. 6 and 7, thus preventing any binding action between the hood and the key carrier disc 9.

It will be noted that, when the continuances 41 of the flanges 36 are brought together in abutting relationship, as aforesaid, there is thus provided an opening 47 in the hood section adjacent the abutting and riveted together ears 37, and adjacent the opening there is a closed portion 48 that is formed by the abutting relationship of the extensions 41 of the flanges 36, and, further, there is an opening 49 in this hood for a purpose later described.

By referring to Figs. 1, 2 and 6, it will be seen that, when the reduced head portion 34 is spring

pressed outwardly through the opening 49 in the hood, one side edge portion 34' of the head will engage the side edge 50 of the closed part of the hood 48 and, in this position of the latch, the key ring will be closed as shown in Fig. 1, and as this side edge portion 34' of the latch 12 is a substantially straight wall, the hood cannot be moved relative to the disc-like element or vice versa and, in other words, these two elements are latched or locked together when they are in the position as shown in Fig. 1. However, by simple depressing of the head 34 of the latch with the fingernail or in any other suitable manner, the hood then can be rotated on the rivet 14 relative to the disc member and, when so rotated, the head 34 of the latch rides under the closed formation 48 of the hood and is depressed and, when it reaches the opening 47, it will, of course, snap up into that opening and, in this position, the gap 18 in the key ring is open as shown in Fig. 2 so that a key or keys may be placed on or removed from the curved arm 27 of the disc. It will be noted that the top of the head 34, as seen in Fig. 2, has one portion thereof 34a inclined and, while the latch is in the position shown in Fig. 2, it will maintain the gap open but, no manual or deliberate depression of the head 34 is necessary because if the hood be moved relative to the disc or vice versa, the pressure of this inclined portion 34a of the head will result in the latch being automatically depressed beneath the closed portion 48 and one of the elements is rotated relative to the other to effect the closed position as shown in Fig. 1 of the drawing. One of the reasons why the key ring, when it is in its locked or latched position as shown in Fig. 1, cannot be opened to the position shown in Fig. 2, is that the shoulder 29 at the end of the curved or semi-circular arm 27 abuts the extreme closed end portion 51, see Fig. 1. Thus, when the latch is in the position as shown in Fig. 1, the shoulder 29 will be engaging the closed end portion 51 of the hood and one of the elements cannot possibly be unintentionally rotated or moved relative to the other and the only way that these two elements can be moved relative to each other is by manually depressing the head 34 of the latch with the fingernail or in any other suitable manner.

I may utilize the key ring on an extensible type key chain or on a more or less conventional key chain K as denoted in the drawings. One end of the key chain has a connecting ring 52 associated therewith and this connecting ring 52 passes through the hollow rivet 15 and serves to connect the one end of the chain to the key ring or vice versa. The other end 53 of the key chain has attached thereto a fastener F, and which fastener may be secured to the usual belt loop L of a garment such as a pair of trousers or the like G. This fastener F is more fully described in a copending application, Serial No. 115,864, filed September 15, 1949. Of course, I may use any type fastener in combination with a chain or an extensible key chain to which the present key ring is attached or associated therewith.

It will be understood that when it is desired to insert a key on or remove a key from the key ring, the elements are in the position as shown in Fig. 2 thereby exposing the gap 18 and this allows a key or keys to be removed or placed on the curved or semi-circular arm 27. When the key H is mounted on this curved arm, as shown in Fig. 1, it is properly held in association

with the key ring and locked thereon and cannot become accidentally displaced or removed therefrom.

I claim:

1. A key ring comprising a disc provided with a radial slot and having an arcuate slot spaced from the periphery of the disc and forming a peripheral key holding arm, said disc being provided at one end of the arm with a peripheral gap communicating with and forming an entrance to the arcuate slot to permit keys to be arranged on and removed from said key holding arm, a hood having spaced sides and arranged on the exterior of said disc and pivoted to the same substantially centrally thereof and movable over the disc to cover and uncover the entrance to the arcuate slot, and latch means located in said radial slot and arranged to engage the hood for holding the same in position for closing the entrance to the arcuate slot and for also holding the hood in position for exposing said entrance to permit keys to be arranged on and removed from the key holding arm.

2. A key ring comprising a disc having an arcuate slot spaced from the periphery of the disc and forming a peripheral key holding arm, said disc being provided at one end of the arm with a peripheral gap communicating with and forming an entrance to the arcuate slot to permit keys to be arranged on and removed from said key holding arm, a hood having spaced sides and arranged on the exterior of said disc and pivoted to the same substantially centrally thereof and movable over the disc to cover and uncover the entrance to the arcuate slot, and latch means separate from the disc mounted between the spaced sides of the hood for movement relative to the disc and hood to latch the hood in position for closing the entrance to the arcuate slot and for also latching the hood in position for exposing said entrance to permit keys to be arranged on and removed from the key holding arm.

3. A key ring including a substantially circular disc having an arcuate slot therein spaced inwardly from its periphery and forming a peripheral key holding arm, the disc being provided at one end of said arm with a peripheral opening communicating with the arcuate slot at one end thereof and providing for keys to be placed on and removed from said key holding arm, and a sector shaped hood enclosing a sector of the disc, the hood comprising two oppositely disposed sections each including a side wall engaging one side wall of the disc substantially centrally thereof, and each section of the hood having at its periphery a laterally and inwardly extending curved flange, means securing the two sections of the hood together with said flanges in abutting relationship at their outer free edges, the disc having an aperture centrally thereof and the side walls of the hood each having an aperture

ture in the apex portion thereof in registry with the aperture in the disc, and a rivet extending through the aperture in the disc and the apertures in the side walls of the hood and connecting the hood and disc for relative rotation providing for positioning the hood to cover and uncover said peripheral opening in the disc.

4. A key ring including a substantially circular disc having an arcuate slot therein spaced inwardly from its periphery and forming a peripheral key holding arm, the disc being provided at one end of said arm with a peripheral opening communicating with the arcuate slot at one end thereof and providing for keys to be placed on and removed from said key holding arm, and a sector shaped hood of slightly greater diameter than the diameter of the disc, the hood having spaced side walls and a peripheral wall portion, the latter corresponding in curvature to the curvature of the circular periphery of the disc, the hood being pivoted at the apex portions of its side walls to the disc substantially centrally thereof for movement relative thereto to positions to cover and uncover said peripheral opening in the disc, the hood enclosing a sector of the disc and when positioned to cover said peripheral opening in the disc, the curved peripheral wall portion of the hood extending over the peripheral opening of the disc, and latch means separate from the disc and mounted thereon between the side walls of the hood for inward and outward movement relative thereto and adapted to engage the peripheral wall portion of the hood to latch the same in position for closing the peripheral opening in the disc, and also in position for exposing said peripheral opening to permit keys to be placed on and removed from the key holding arm.
